UNITED STATES PATENT OFFICE

ELIHU THOMSON, OF LYNN, MASSACHUSETTS.

COUPLING DYNAMO-ELECTRIC MACHINES.

SPECIFICATION forming part of Letters Patent No. 367,866, dated August 9, 1887.

Application filed June 4, 1886. Serial No. 204,129. (No model.)

To all whom it may concern:

Be it known that I, ELIHU THOMSON, a citizen of the United States, and a resident of Lynn, in the county of Essex and State of Massachusetts, have invented certain new and useful Improvements in Coupling Dynamo-Machines, of which the following is a specification.

My invention relates to dynamo-electric machines coupled in multiple arc to an electric circuit.

My invention is designed especially for application to dynamo-machines when coupled in multiple arc, and at the same time provided with an equalizing-connection, such as described in the patent of E. W. Rice, No. 328,253, dated October 12, 1885.

The object of my invention is to prevent the injury which would result from the slipping of the driving-belt for one armature; and to this end the invention consists in placing a fusible plug in the connection from each armature to the outside circuit or main, such plug being located at a point between the armature and the point where the equalizing-connection between the two armatures is made.

My invention is shown as applied to the case of compound wound dynamo-machines.

The drawing illustrates the invention diagrammatically.

The armatures of the two machines are indicated at A A', respectively, and their derived-circuit field-coils are indicated at S S', respectively.

D D' indicate the direct-circuit field-coils, and E the equalizing-connection, which con-

nexion is a low-resistance wire joining the machine-circuits between their armatures and their direct-field coils.

M M' are the mains to which the dynamos are coupled in multiple arc, and L the incandescent lamps or other translating devices.

The plugs P P' are inserted in the circuit between the armature and the field-magnet coils, as shown.

The equalizer is connected at a point between the field-magnet coils and the plugs or safety-catches.

If the belt driving one armature, A, should slip off, or the electro-motive force of A should fall off greatly from any other cause, a short circuit would be formed from armature A' through P' E P, armature A, and back to A' to connection b. The plugs P P', one or both, would then melt and interrupt the short circuit formed, thus saving both armatures from injury.

What I claim as my invention is—

The combination, with compound wound dynamo-machines connected in multiple arc, and provided with an equalizing-connection, as described, of fusible plugs or safety-catches located between the armatures and the equalizing-connection.

Signed at Lynn, in the county of Essex and State of Massachusetts, this 28th day of May, A. D. 1886.

ELIHU THOMSON.
